Application July 12, 1940, Serial No. 345,168

20 Claims. (Cl. 47—3)

This invention relates to a web applying and/or affixing machine adapted among other uses for applying bleaching paper to celery and other crops.

The invention has for an object to provide a novel and improved machine of the character specified in which provision is made for applying the web, such as bleaching paper, on the opposite sides of a row of celery plants or other growing crop and for thereafter automatically placing wire staples over the row to hold the paper firmly in place against the plants.

Another object of the invention is to provide a novel and improved machine of the character specified in which provision is made for automatically affixing fastening members over a row of celery to which bleaching paper has been applied in a novel, rapid and efficient manner.

With these general objects in view and such others as may hereinafter appear, the invention consists in the bleaching paper applying and affixing machine, in the affixing machine alone and in the various structures, arrangements and combinations of parts hereinafter described and particularly defined in the claims at the end of this specification.

In the drawings illustrating the preferred embodiment of the invention, Fig. 1 is a side elevation of a machine embodying the present invention; Fig. 2 is a front elevation of the machine shown in Fig. 1 with the staple magazine and the bleaching paper rolls removed; Fig. 3 is a rear elevation of the same; Fig. 4 is a plan view of the bleaching paper applying mechanism; Fig. 5 is a front elevation of the wire staple magazine; Fig. 6 is a partial plan view of the magazine; Figs. 7 and 8 are detail views of a traveling gripper jaw unit as viewed from opposite sides; Fig. 7 showing a front elevation of a gripper unit on the further side of the machine as viewed from the line 7—7 in Fig. 2, and Fig. 8 is a similar view showing a front elevation of a corresponding gripper unit in a different position of operation as viewed from the line 8—8 in Fig. 2; Fig. 9 is a cross-sectional view taken on the line 9—9 of Fig. 1; and Fig. 10 is a cross-sectional detail taken on the line 10—10 of Fig. 1.

In general, the present invention contemplates a novel web applying and affixing machine comprising generally a frame structure provided with wheels and which, among other uses, is adapted to be propelled over a row of celery or other growing crop to be bleached. The unit is arranged to straddle the row and is preferably provided at its forward end with two rolls of

bleaching paper, one upon each side of the row, which are arranged to be unwound from the rolls to provide strips of bleaching paper upon the opposite sides of the row as the machine is propelled forward. Provision is also made in the preferred embodiment of the invention for automatically placing wire staples over the bleaching paper thus applied, and in the preferred machine, a magazine is provided adapted to hold a supply of the wire staples. A plurality of traveling gripper jaws are arranged to withdraw the staples from the magazine and to place them in straddling relation over the row of celery and the bleaching paper, as the machine is propelled forwardly over the row, preferably, but not necessarily, forcing the ends of the staples into the ground. The traveling gripper jaws may be mounted upon an endless chain arranged to travel in a downwardly inclined path from the forward portion of the machine toward the rear thereof, and the jaws are designed to hold the wire staples in vertical relationship to the ground as they are urged downwardly during the forward movement of the machine by the angular relationship between the inclined chain and the ground.

Provision is preferably made for driving the traveling gripper jaws through the rearwardly inclined path provided therefor at a rate of speed such that the horizontal component of such angular movement will be exactly equal to the forward movement of the machine being propelled over the row, so that, in effect, the wire staple moves only vertically and in a downward direction during the operation of the machine. This relationship is preferably maintained through driving connections from the wheels. Provision is also made for controlling the operation of the jaws to open and close the same at the proper times and the jaws may also be arranged to be moved laterally in an inward direction during the wire placing operation in order to press each side of the wire staple up close against the bleaching paper to hold it snugly against the row of plants.

Referring now to the drawings illustrating the preferred embodiment of the invention, the machine comprises, in general, a pair of rectangular side frames or plates 10, 12 rigidly supported in spaced relation and which are provided with two pairs of wheels 14, 16 arranged to straddle the row of plants over which the machine is propelled. The forward portion of the machine is provided with a bleaching paper applying device, indicated generally at 18 which is arranged to place strips 20 of the bleaching paper against the

opposite sides of the row 22 of celery or other growing crop. The machine is further provided with mechanism for placing wire staples 24 over the strips of bleaching paper and preferably into the ground and such mechanism may include a magazine 26 for holding a supply of the wire staples 24, and a plurality of traveling gripper jaws 28 arranged to withdraw successive wire staples from the magazine and to insert the ends thereof into the ground as the machine progresses over the row.

As herein shown, the wheels 14, 16 are secured to the individual hub members 30 which are arranged to rotate freely upon studs 32 fixed in the side plates 10, 12 and extending outwardly therefrom. Collars 34 are provided upon the outer ends of the studs in order to hold the wheels in place. The side plates are rigidly secured together in spaced relation by tie pieces including channel bars 36 adjustably secured to angle members 38 attached to the side plates, as illustrated in Figs. 1, 2 and 3. Angular tie pieces 40, 42 are provided at the rear of the structure and are arranged in overlapping relation to permit lateral adjustment of the unit. The forward portion of the machine is rigidly secured together by the interposition of the wire staple magazine 26 to which reference will be made.

Referring now to Figs. 1 and 4, the bleaching paper applying device 18, may comprise a pair of roll carrying units 44, 46 secured to the side plates 10, 12 by angle members 48, 50 and which are provided with wheels 49, 51 at their forward end. Each roll carrying unit is provided with a spindle 52 which is slightly inclined inwardly and upon which supply rolls 54 of the bleaching paper are rotatably mounted. The disposition of the supply rolls 54 at a slight incline from a vertical position tends to urge the lower edge of the paper toward the ground and to maintain the edge in this position as the paper is unwound from the rolls during the operation of the machine. Suitable braking means, not shown, may be provided for the supply rolls to prevent the bleaching paper from unwinding too freely. Provision is also made for guiding and yieldably urging the paper against the opposite sides of the row of celery as it is unwound from the rolls, and as herein shown, such means may comprise pivotally mounted pressers 56 which are supported upon brackets 58 attached to the angle members 48, 50 and which are rocked in a direction such as to urge the trailing ends of pressers against the paper and the opposite sides of the celery by springs 60, as clearly shown in Fig. 4.

As illustrated in Figs. 1, 5 and 6, the wire staple magazine 26 is adapted to hold a bulk supply of the wire staples 24 and to advance them toward the delivery end of the magazine as they are withdrawn therefrom by the gripping jaws 28 so that the foremost wire staple in the magazine is always in a position to be gripped and withdrawn by a succeeding set of gripping jaws 28 when the latter are brought into gripping position. The magazine is supported between the side plates 10, 12 at the forward end of the machine and between extension plates 62, 64 attached to the side plates 10, 12 respectively. The extension plates 62, 64 are rigidly tied together by overlapping angle brackets 66, 68 which are arranged with slotted portions to permit of lateral adjustment.

The wire staples are supported in the magazine upon an overhanging unitary structure comprising a T-bar 70 and a pair of guide bars 72, 74. 75

These members are supported from the rear end of the magazine upon an inverted U-shaped bracket 76, the lower end of which rests upon the tie bracket 66, as shown in Fig. 5. The members 70, 72, 74 are tied together at the forward or delivery end of the magazine by a shortened inverted U-shaped bracket 75. The wire staples are hung upon the overhanging structure with the looped portions thereof resting upon the top of the T-bar 70 and the depending legs thereof resting against the guide bars 72, 74 all disposed within the confines of the open portion of the staples.

Additional guides and retaining members 77, 78, 80 are provided for supporting and guiding the outer portion of the staples. As herein shown, see Figs. 1 and 5, the upper guide member 77 is arranged to prevent vertical displacement of the staples and is supported by angle brackets 82 extending from the side plate 10. The forward end of the guide bar is provided with a hooked portion 84 against which the foremost staple in the stack may rest and which is operative to retain the stack in the magazine upon pressure from the rear of the stack and to prevent withdrawal of the foremost staple except in a downward direction. The guide members 78, 80 are supported from the side plates 10, 12 by angle brackets 86, 88 and are arranged to cooperate with the inner guide members 72, 74 to prevent lateral displacement and to guide the staples as they are advanced therethrough as will be described. The members 78, 80 are also provided with hooked retaining portions 90 to prevent withdrawal of the wires 24 from the stack except in a downward direction.

Provision is made for advancing the stack of staples in the magazine as they are successively withdrawn therefrom and to hold the stack in yielding engagement with the retaining portions 84, 90 in order to keep the foremost staple from falling out. As shown in Fig. 1, the foremost staple 24 is projected beyond the inner supporting structure and is held in position to be gripped by the jaws 28 merely by the pressure of the stack against the back of the staple and by the hooked retaining portions 84, 90. As herein shown, a pair of spiral springs 92, 94 are provided at the forward end of the magazine, each of which is attached to an engaging member 96, 98 arranged to be hooked over the end of the stack, as shown in Fig. 6. The spiral springs 92, 94 which are made up from a flat band or strip of steel similar to a clock motor spring are wound in a manner such as to provide a constant tension upon the engaging members against the back of the stack. As herein shown, the upper spring 92 is supported upon a stud 100, which is mounted between arms 104 attached to the T-bar 70, as shown in Figs. 1 and 5. A portion of the T-bar is cut out as indicated at 106 to provide clearance for the upper spring member 92. The lower spring member 94 is supported upon a stud 108 which is mounted between the arms 110 attached to and extending from the inverted U-shaped bracket 75, see Figs. 1 and 6. Although as illustrated, both engaging members 96, 98 are in engagement with the back of one stack of wires, in practice, when the supply of staples in one stack has been nearly depleted, another stack may be inserted into the magazine whereupon one of the engaging members may be detached from the first stack and hooked over the newly inserted stack. In practice, the staples are prepared in bundles of convenient size to be in-

serted in the magazine so that when the staples being urged forwardly by one engaging member are depleted, this engaging member is drawn back and engaged with a new stack. As illustrated in Fig. 1, a hinged member 112 pivoted at 114 which normally rests in the position shown in full lines in Fig. 1 to serve as an extension of the upper guide 71, is arranged to be rocked upwardly as shown in dotted lines to permit insertion of additional staples into the magazine.

Various arrangements may be provided for feeding the wires into operative position in the magazine to be withdrawn by the gripper jaws, the above being merely illustrative of one of the preferred forms of feeding devices. For example, the T-bar 70 may be extended horizontally at its upper end and the staples, hung on such extension, may be fed by gravity into the receiving end of the magazine instead of placing the bundles in from the top, as above illustrated. Also, the wires may be in a rack and fed cartridge-like into the wire magazine.

Referring now to Figs. 7 and 9, the traveling gripper jaws 28 are arranged in pairs, one upon each side of the staple, and are arranged so that each jaw will grip one of the two depending legs of the staple. The jaws are carried by two endless chains 120 and suitable guiding and controlling means arranged symmetrically upon either side of the structure, and as each group of jaws is similar in construction and operation, a description of one will suffice for both. The endless chain 120 is arranged to run over sprockets 122, 124, one of which, 122, is driven through connections from the rear wheels 16, as will be described. The driven sprocket 122 is keyed to a shaft 126 which is supported from the side plate 10 in a bearing member 128. The idler sprocket 124 is mounted upon a shaft 130 journalled in a bearing member 132 attached to the side plate 10, as shown in Figs. 9 and 10.

As illustrated in detail in Figs. 7 and 9, each gripping jaw unit comprises a main bearing member 134 which is carried by a bracket 136 attached to a suitable adapter 138 connected to a link of the chain 120. Provision is made for guiding the unit including the bearing member 134 and bracket 136 through a fixed and rigid path as it is carried around by the chain, and as herein shown, each bracket 136 is provided with guide rollers 140 arranged to run in tracks or gibs 142, 144 disposed symmetrically upon either side of the endless chain. The gibs 142, 144 are supported upon the shafts 126, 130 as clearly shown in Figs. 9 and 10, and each shaft is provided with a collar 146 at its inner end to hold the members in operative relation.

Each gripping jaw unit includes two pairs of jaws arranged to grip the depending leg of the staple at spaced points. One of the jaws 148 of each pair is relatively stationary being formed as part of a two-armed member 150 having a central hub 152 extending into the main bearing 134. The two-armed member is fixed to a shaft 154 having a cylindrical portion 155 extending through the hub 152 and a square portion 156 extending through a hub 158 of the mechanism for effecting relative rotation of the unit to keep the jaws in a vertical position as they travel through the inclined path, as will be described. The other jaw 160 of each pair is arranged to be opened and closed and to cooperate with the relatively stationary jaws 148 to grip the staple and withdraw it from the magazine and to insert the ends thereof into the

ground. As herein shown, the movable jaws 160 are mounted fast upon a shaft 162 journalled in the hubs of the relatively stationary jaws 148 and the shaft 162 is further provided with a cam lever 164 having a roller 166 which is arranged to cooperate with a stationary cam piece 168 mounted adjacent the track, as shown in Figs. 7 and 9. A spring 170 is provided to hold the roller 166 against its cam, and which normally urges the movable jaws into closed position when the roller rides off its stationary cam.

In order to control the jaw carrying unit in a manner such that the upper and lower pairs of jaws will be retained in vertical alignment, provision is made for effecting rotation of the unit as it travels through the inclined path, and as herein illustrated, the outer end of the shaft 154 is provided with a cam lever 172 having a roller 174 arranged to cooperate with a stationary cam piece 176. The cam lever 172 formed integrally with the hub 158 is fitted over the square portion 156 of the shaft. The lever is provided with slotted portions 178 and is attached to a flanged portion 180 of the main bearing 134 by screws 182 in a manner such as to permit relative rotation, as defined by the slotted portions 178.

From the description thus far it will be observed that when the gripping jaw unit arrives at a position in front of the wire staple magazine, as shown in Fig. 7, the movable jaws will be caused to close upon the foremost staple, and to pull the staple downwardly out of the magazine. It will also be observed that the stationary cam 176 is designed to hold the unit in an angular position during the withdrawal movement, and thereafter, when the staple has been advanced beyond the influence of the magazine, the jaw unit is rotated to dispose the staple in a vertical position and this relationship is maintained during the wire placing or inserting operation, as illustrated in Fig. 8. As therein shown, a spring 184 is provided to hold the roller 174 against its cam piece 176. The cam piece 176 is supported at its forward end from the side plate by a bolt 186 and spacing members 188, as shown in Fig. 9, and may be similarly supported at its other end by an extension 189, as shown in Fig. 1.

Provision is made in the preferred embodiment of the invention for projecting the gripping jaw unit inwardly, against the sides of the row of celery in order to place the depending legs of the staples snugly against the bleaching paper. As illustrated in Figs. 8 and 9, the outer end of the square portion 156 of the shaft 154 is provided with a shouldered or grooved portion 190 arranged to be engaged by a latch member 192 to normally lock the unit in the position shown in Fig. 9. The latch is pivoted at 194 in the cam lever 172 and is provided with a spring 196 to hold the latch in place in the grooved portion 190. Thus each set of jaws is held in a position to grasp the depending legs of the wire to withdraw it from the magazine. When the unit arrives at a predetermined position, and at about the time when the ends of the wires contact with the ground, the latch is arranged to be withdrawn to permit the unit to be projected inwardly as described. The latch 192 is provided with a trip lever 198 which is arranged to engage a tripping member 200 mounted upon an extension 202 from the side plate as shown in Fig. 1. Upon engagement with the tripping member 200, the shaft 154 and the gripping unit

is projected inwardly by a coil spring 204 which is interposed between the hubs 152 and 158. The spring 204 is of sufficient resiliency to urge the wires close against the bleaching paper and is arranged to be stopped in its inward movement by the resistance of the paper and the plants. The shaft is held from being withdrawn entirely from the unit by a limiting pin 206 fixed in the shaft which extends into a slot 208 provided in the hub 158. In the operation of the machine, the unit is maintained in its inwardly projected position during the remainder of the wire inserting operation. Provision is made for resetting the unit into its latched position during the travel of the jaws through the upper or return path of the unit, and for this purpose a roller 210, provided upon the movable jaw shaft 162, is arranged to cooperate with a stationary cam piece 212 mounted upon a bracket 213 supported from the tie piece 40, as illustrated in Fig. 1.

Provision is also made for opening the gripper jaws when the wire staple is inserted to the desired depth, and as shown in Fig. 1, a stationary cam piece 214, similar to the cam piece 168, is provided adjacent the gibs at the lower end of the unit. After leaving the cam piece 214, the jaws will be closed and will remain in their closed position until they are again opened by the cam piece 168 when they arrive at the magazine to withdraw a succeeding wire staple, as hereinbefore described. Although the wires are preferably extended into the ground, it will be apparent that the object of the invention may also be attained by merely extending the ends of the wires to the ground and then bending the legs inwardly as above described.

As above stated, the traveling gripper jaws 28 are arranged to be driven through connections from the rear wheels 16 of the structure, and as herein shown, see Figs. 1, 2 and 3, the hub 30 of each rear wheel 16 is provided with a sprocket 216 fast thereon which is connected by a chain 218 to a sprocket 220 fast on the outer end of the shaft 126. Each chain 218 is arranged to run over an idler sprocket 222 mounted upon an intermediate shaft 224 which is supported in bearings 226 attached to the side plates 10, 12, as shown in Fig. 3. The idler sprockets 222 are held fast upon the shaft 224 by keys 228 which are arranged to slide in elongated key slots 230 to provide for lateral adjustment of the side plates. Thus, the two separately driven traveling gripper units are tied together through the common intermediate shaft 224 so that after they have been initially adjusted to operate in unison they will be retained in such operative relation.

In order to provide sufficient traction against the ground, the wheels may be provided with traction blades or spikes, as indicated at 232. In some instances, it may be desired to provide a caterpillar drive, between the forward and rear wheels. Although the structure is arranged to be propelled manually or towed by a tractor, provision may be made for driving the unit by any usual or preferred form of motive power, such as a gasoline powered engine, indicated by dotted lines at 234. When such auxiliary power plant is employed, it may be connected by a belt or chain drive 236 to the intermediate shaft 224.

In the operation of the machine, when the portable structure is propelled over the row of growing plants, the strips of bleaching paper are unwound from the rolls thereof, having been initially secured together around the end

of the row as indicated at 238 in Fig. 4. The rotation of the rear wheels 16, as the machine progresses over the row, operates to drive the traveling gripper jaws 28, as above described, and when a set of gripping jaws arrives into operative position with relation to the magazine, the foremost staple is gripped and removed from the magazine, whereupon the stack of staples in the magazine is advanced to present a succeeding staple in position to be removed by the succeeding set of gripper jaws. As the traveling gripper unit is moved through the inclined path, it is held in a vertical position by the cooperation of the stationary cam 176 and roller 174 so as to hold the wire staple vertically with relation to the ground during their travel. Thereafter, the latch mechanism 192 is tripped to project the jaw units laterally against the opposite sides of the row and against the bleaching paper. The driving mechanism between the rear wheels and the traveling jaw mechanism are so designed as to cause the jaws to be carried down the rearwardly inclined path at a rate of speed such that the horizontal component of such angular movement will be exactly equal to the forward motion of the structure passing over the row, so that the resultant motion will be entirely vertical when the ends of the staples are being inserted into the ground and with no lateral movement whatever with relation to the ground. As the jaws travel downwardly, the staples are forced into the ground in a vertical position. When the staples have been inserted into the ground to the desired depth, the jaws are released, whereupon they are reset and returned to pick up another wire staple.

From the above description it will be observed that the present bleaching paper applying and affixing machine is adapted to be adjusted laterally in order to accommodate different widths of rows. The present machine may also be adapted to insert the staples at various depths or merely to the ground surface by arranging the staple magazine with relation to the gripper unit so that the staples may be gripped at different heights. Thus, when the staples are gripped at a relatively high point, they will be caused to enter the ground earlier than when gripped at a lower point, and consequently, they will be inserted deeper into the ground. Likewise, the depth may be regulated by changing the position of the jaw releasing cam 214, so that when the staples are inserted to the desired depth, the jaws will release their grasp upon the wires and prevent further downward action. Furthermore, the unit may be provided with a greater or lesser number of sets of jaws, spaced closer together or farther apart, in order to vary the spacing between the staples along the row. As illustrated in Fig. 10, provision is made for adjusting the lower bearing 132 longitudinally by the provision of a slotted portion 240. Such adjustment may be utilized in order to bring the lower end of the unit closer to the ground to enable the staples to be planted deeper, or the adjustment may be used to accommodate different lengths of chain upon which the jaws are arranged in different spaced relation. In any event, the adjustment provided for the lower bearing 132 tends to keep the chain 120 taut between the sprockets 122, 124.

While the machine is particularly adapted for use in the application of bleaching paper strips to celery, it will be understood that it may be used for applying any desired web or webbing

strips to any rows of growing plants. It will also be understood that the device may be used independently as an affixing unit to place the wires over a row which has been previously provided with strips of bleaching paper.

While the preferred embodiment of the invention has been herein illustrated and described, it will be understood that the invention may be embodied in other forms within the scope of the following claims.

Having thus described the invention, what is claimed is:

1. In a machine of the character described, in combination, a portable unit adapted to be propelled over a row of growing plants, means carried by said unit for applying webs upon opposite sides of the plants as the unit is propelled forwardly, and means also carried by said unit for automatically applying retaining members upon the opposite sides of said row adjacent said webs.

2. In a machine of the character described, in combination, a portable unit provided with wheels adapted to straddle a row of growing plants, a pair of rolls of webbing mounted upon the forward portion of said unit and arranged to be unwound to apply webs upon opposite sides of the plants as the machine is propelled forwardly, and means carried by said unit operative to apply retaining members adjacent said applied webs at spaced intervals along the row.

3. In a machine of the character described, in combination, a portable unit provided with wheels adapted to straddle a row of growing plants, means carried by said unit for applying webbing strips upon opposite sides of the plants as the unit is propelled forwardly, means for pressing said strips into contiguous engagement with the opposite sides of said plants, and means also carried by said unit for applying retaining members adjacent said webbing strips at spaced intervals along said row during the forward movement of said unit, whereby to retain said strips in contiguous engagement with said plants.

4. In a machine of the character described, the combination with means for applying strips of paper upon opposite sides of a row of growing plants, of means for applying paper retaining members adjacent said strips at spaced intervals along said row during the forward movement of the machine.

5. In a machine of the character described, the combination with portable means for applying webbing strips upon the opposite sides of a row of growing plants, of means for applying wire staples adjacent said strips at spaced intervals along said row.

6. In a machine of the character described, the combination with portable means for applying webbing strips upon the opposite sides of a row of growing plants, of means for applying wire staples adjacent said strips at spaced intervals along said row, said means comprising a traveling carrier chain having a plurality of movable jaws thereon adapted to grasp said staples and to insert the ends thereof into the ground.

7. In a machine of the character described, the combination with portable means for applying webbing strips upon the opposite sides of a row of growing plants, of means for applying wire staples adjacent said strips at spaced intervals along said row, said means comprising a traveling carrier chain having a plurality of movable jaws thereon adapted to grasp said staples and to

insert the ends thereof into the ground, said carrier chain being arranged to move said jaws through a downwardly inclined path toward the rear of the machine, and means for retaining said jaws in a vertical position with respect to the ground as they travel through said inclined path.

8. In a machine of the character described, in combination, a portable unit provided with wheels and being adapted to straddle a row of growing plants, a pair of rolls of webbing mounted upon the forward portion of said unit and arranged to be unwound to apply strips upon opposed sides of the plants as the machine is propelled forwardly, and means carried by said unit for automatically inserting wire staples over said row and into the ground.

9. In a machine of the character described, in combination, a portable unit adapted to straddle a row of growing plants, a chain mounted on said unit and angularly arranged with respect to the ground, a plurality of gripper jaws carried by said chain, a magazine adapted to hold a plurality of wire retaining members, jaw operating means for successively withdrawing said members from the magazine, and means for holding said jaws in a vertical position with respect to the ground as they are carried through said angular path, said chain being adapted to travel through said angular path at a rate of speed such that the horizontal component of such angular movement will be substantially equal to the forward movement of the machine.

10. A machine of the character described comprising a portable unit provided with wheels adapted to be propelled over a row of growing plants to which bleaching or other webs have been previously applied, and means carried by said unit for automatically applying retaining members upon the opposite sides of said row adjacent said webs at spaced intervals along the row during the forward movement of said unit, whereby to retain said webs in contiguous engagement with said plants.

11. A machine of the character described comprising a portable unit adapted to be propelled over a row of growing plants to which bleaching or other webs have previously been applied, and means carried by said unit for applying wire staples adjacent said webs at spaced intervals along the row, said means including an endless traveling carrier chain having a plurality of movable jaws thereon adapted to grasp said staples and to place them in operative position against said webs to retain the latter in contiguous engagement with said plants.

12. A machine of the character described comprising a portable unit adapted to be propelled over a row of growing plants to which bleaching or other webs have previously been applied, and means carried by said unit for applying wire staples adjacent said webs at spaced intervals along the row, said means including an endless traveling carrier chain having a plurality of movable jaws thereon adapted to grasp said staples and to place them in operative position against said webs to retain the latter in contiguous engagement with said plants, said carrier chain being arranged to travel in a downwardly inclined path toward the rear of the machine, and means for retaining said jaws in a vertical position with respect to the ground as they travel through said inclined path.

13. A machine of the character described comprising a portable unit adapted to be propelled

over a row of growing plants to which bleaching or other webs have previously been applied, and means carried by said unit for applying wire staples adjacent said webs at spaced intervals along the row, said means including an endless traveling carrier chain having a plurality of movable jaws thereon adapted to grasp said staples and to place them in operative position against said webs to retain the latter in contiguous engagement with said plants, said carrier chain being arranged to travel in a downwardly inclined path toward the rear of the machine, and means for retaining said jaws in a vertical position with respect to the ground as they travel through said inclined path, said chain being arranged to travel through said rearwardly inclined path at a rate of speed such that the horizontal component of such angular movement will be equal to the forward movement of the machine being propelled over the row.

14. In a machine of the character described, the combination with portable means for applying webbing strips upon the opposite sides of a row of growing plants, of means for applying wire staples at spaced intervals along said row, including a movable wire holding member, and means for guiding said holding member through a downwardly and rearwardly inclined path, said holding member being adapted to hold said wire in a vertical position with relation to the ground while traveling through said inclined path, said holding member being arranged to travel through said rearwardly inclined path at a rate of speed such that the horizontal component of such angular movement will be equal to the forward movement of the machine being propelled over the row.

15. A portable unit adapted to be propelled over a row of growing plants to which bleaching or other webs have been previously applied comprising mechanism for placing retaining members over said row including a movable holder arranged to hold a retaining member in a vertical position, means for moving said holder downwardly to place the retaining member over the row, and means for moving said holder rearwardly at a rate of speed equal to the forward movement of the unit whereby to hold said retaining member relatively stationary in a lateral direction while it is moving vertically downward.

16. In a machine of the character described, in combination, a portable unit provided with wheels adapted to straddle a row of growing plants, means carried by said unit for applying bleaching or other strips upon opposite sides of the plants as the unit is propelled forwardly, and means also carried by said unit for applying retaining members adjacent said bleaching strips at spaced intervals along the row during the forward movement of said unit, said last named means including a traveling carrier chain having a plurality of gripper jaws mounted thereon, said carrier chain being arranged to move said jaws through a downwardly inclined path toward the rear of the machine, a magazine adapted to hold a plurality of wire retaining members, means for advancing said wire retaining members in the magazine to present the foremost wire into operative relation to said jaws, means for operating said jaws to grasp and withdraw successive wires from the magazine, and means for retaining said jaws in a vertical position with respect to the ground as they travel through said inclined path, said chain being arranged to travel through said rearwardly inclined path at a rate of speed

such that the horizontal component of such angular movement will be equal to the forward movement of the machine being propelled over the row.

17. In a machine of the character described, in combination, a portable unit provided with wheels adapted to straddle a row of growing plants, means carried by said unit for applying bleaching or other strips upon opposite sides of the plants as the unit is propelled forwardly, and means also carried by said unit for applying retaining members adjacent said bleaching strips at spaced intervals along the row during the forward movement of said unit, said last named means including a traveling carrier chain having a plurality of gripper jaws mounted thereon, said carrier chain being arranged to move said jaws through a downwardly inclined path toward the rear of the machine, a magazine adapted to hold a plurality of wire retaining members, means for advancing said wire retaining members in the magazine to present the foremost wire into operative relation to said jaws, means for operating said jaws to grasp and withdraw successive wires from the magazine, and means for retaining said jaws in a vertical position with respect to the ground as they travel through said inclined path, said chain being arranged to travel through said rearwardly inclined path at a rate of speed such that the horizontal component of such angular movement will be equal to the forward movement of the machine being propelled over the row, and means operatively connected to said wheels for driving said chain in timed relation to the forward movement of the unit to produce such relative movement.

18. A machine of the character described comprising a portable unit adapted to be propelled over a row of growing plants to which bleaching or other webs have previously been applied, and means carried by said unit for applying wire staples adjacent said webs at spaced intervals along the row, said means comprising a pair of opposed endless traveling carrier chains having a plurality of movable jaws thereon, opposing jaws forming pairs arranged to grasp both legs of a staple and to place it in operative position against said webs to retain the latter in contiguous engagement with said plants.

19. A machine of the character described comprising a portable unit adapted to be propelled over a row of growing plants to which bleaching or other webs have previously been applied, and means carried by said unit for applying wire staples adjacent said webs at spaced intervals along the row, said means comprising a pair of opposed endless traveling carrier chains having a plurality of movable jaws thereon, opposing jaws forming pairs arranged to grasp both legs of a staple and to place it in operative position against said webs to retain the latter in contiguous engagement with said plants, said opposed wire placing jaws having provision for being projected inwardly towards each other to press the legs of the staple against said webs.

20. In a machine of the character described, the combination with portable means for applying webbing strips upon the opposite sides of a row of growing plants, of means for applying wire staples at spaced intervals along said row including a pair of opposed traveling carrier chains having a plurality of movable jaws thereon, opposing jaws forming pairs arranged to grasp opposing legs of a staple and to place it in operative position against said webs to retain the lat-

ter in contiguous engagement with said plants, said carrier chains being arranged to move said jaws through a downwardly inclined path toward the rear of the machine, staple feeding means, jaw operating means, means for retaining said jaws in a vertical position with respect to the ground as they travel through said inclined path, said chains being arranged to travel

in unison through said rearwardly inclined path at a rate of speed such that the horizontal component of such angular movement will be equal to the forward movement of the machine being propelled over the row.
